UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,087,140.

Specification of Letters Patent.

Patented Feb. 17, 1914.

Application filed August 4, 1911. Serial No. 642,296.

To all whom it may concern:

Be it known that I, JOHN R. ROGERS, a citizen of the United States, and a resident of Brooklyn, county of Kings, and State of New York, have invented a new and useful Improvement in Typographical Machines, of which the following is a specification.

My invention relates to typographical machines, and more particularly to that class thereof known to the public under the name "Linotype", and as represented for instance in U. S. Letters Patent to O. Mergenthaler, No. 436,532. In this type of machine, circulating matrices are composed in line and presented to the face of a slotted mold, in which a slug or printing bar is cast against them, after which they are returned through a distributing mechanism to their magazine.

My improvement has reference to means for insuring the proper presentation and accurate alinement of the matrices in front of the mold, so as to determine the location of the characters on the edge of the slug, and also to means for preventing the operation of the casting mechanism unless the matrices are in such correct position. After the line is assembled, it is transferred horizontally to a vertically movable support, commonly known as the first elevator, and is lowered thereby to a position in front of the slotted mold, which then advances facewise against the edges of the matrices, after which the elevator is moved slightly upward in order to insure the vertical alinement of the matrices, by causing the cars at their lower ends to rise beneath and against a horizontal shoulder or keeper on the mold.

In the ordinary use of these machines, it is common practice to substitute for one set of matrices another set having characters of different size, and also to adjust the mold so as to vary the thickness of the slug therein, the location of the characters on the slug being determined by the relation which the matrices bear to the mold. The characters stand in inverted position on the matrices, and it was formerly the practice to aline these characters at the top thereof, in other words, matrices of all fonts had a common alining level in the machine at the heads of the characters. Under the recently inaugurated system, matrices of various sizes are also arranged to have a common alinement at the base of the characters. When the

older matrices with the top alinement are used, the elevator descends always to one and the same level, but if matrices with the base alinement are employed, the elevator is required to descend different distances in order to present the matrices in proper relation to the mold, and these distances must be varied to some extent, according to the size of the characters employed and the thickness of the slugs which the mold is adjusted to produce. It is therefore necessary to control the descent of the elevator with precision, and in some cases to adjust the alining shoulders on the mold vertically or to replace them by shoulders in a different position. Machines of this class are ordinarily provided with an automatic device actuated by the descending elevator to control the driving clutch, so that if the elevator fails to present the matrix line at the predetermined level, the operation of the casting mechanism will be arrested. Such clutch controlling devices are generally of the form shown in the before mentioned Patent, No. 436,532. In linotype machines as now constructed, a considerably larger amount of adjustment is provided for than formerly, and it is therefore necessary to insure the control of the clutch devices, notwithstanding the greater range covered by the parts. In my previous application for Letters Patent, Serial No. 553,424, filed April 2, 1910, I have shown mechanism of the same general character as set forth herein. However, the specific devices as therein illustrated would not readily adapt themselves to the greater extent of adjustment herein contemplated, and for that reason I have devised the form of mechanism illustrated in the accompanying drawings. To take a specific instance, certain linotype molds are now capable of producing characters varying in size from 5½-point to 36-point, and the difference between these extremes amounts substantially to 7/16 of an inch. My present improvements are readily capable of adaptation to such an extreme difference and even to a larger one, if such be desired.

In the accompanying drawings I have shown my improvements in preferred form, but obviously many changes and variations may be made therein without departing from the spirit of the invention, and generally speaking, I desire it to be distinctly understood that I do not limit myself to

any specific form or embodiment except in so far as such limitations are specified in the claims.

Referring to the drawings: Figure 1 is a front view of the mold and connected devices of a linotype machine with my invention applied thereto, certain of the parts being broken away for the sake of clearness; Fig. 2 is a vertical section thereof; Fig. 3 is a detached perspective view of the principal elements of my invention; and Fig. 4 is a side view of some of these parts.

The mold wheel O, carrying the slotted molds o, o², is arranged as usual in the vise frame A, and is mounted to rotate intermittently and also to move horizontally in order to carry the mold proper o, to and from the matrices Y, the mold being closed at one side by the matrices and at the opposite side by the pot mouth P, all in the usual manner. The vertically movable first elevator N receives the line at a point higher than that shown in the drawings, and then descends and lowers it to the casting level in front of the mold, which is at such times retracted in order to permit the free passage of the lugs or shoulders at the bottom of the matrices, and after the matrices have reached the casting position, the mold advances toward them. To the face of the mold there is rigidly secured the so-called keeper plate H, having on its face one or more horizontal grooves H¹, H², to engage the ears of the matrices and effect their accurate alignment when the elevator N is moved upward, as occurs after the advance of the mold. In the present instance, the matrix is shown as provided with two independently usable characters, one above the other, and it will be set into the line at a higher or lower level according as one character or the other is to be employed, and the lower ear thereof will consequently engage in one or the other of the grooves H¹, H², according to the height of the matrix in the line.

So far as described, the parts may be of the ordinary construction and have the ordinary mode of operation.

For the purpose of controlling the main clutch which governs the casting mechanism, and of throwing the parts out of action if the matrix line is not lowered to the proper point, a rod a²³ is provided, its upper end being guided in the frame and its lower end being sustained by a spring a²⁴, in such manner as to hold the rod normally in its uppermost position and at the same time to permit a limited lateral movement thereof. The lower end of this rod bears against one end of a pivoted lever a²², which acts at its opposite end against a bar a²¹, arranged to throw the main clutch out of operation. The rod a²³ is provided with a lip a²⁵, and receives its motion to throw the clutch from a horizontal slide a²⁶, mounted in the frame A in

position to be acted upon and pushed forward by the mold wheel O as the latter is shifted against the matrices. These last mentioned parts have a similar mode of action and correspond to the parts indicated by like letters of reference in the previously mentioned Patent, No. 436,532.

The elevator N is provided with means, such as the adjustable screw N¹, in position to contact with the end of the vertically sliding bar a²³, which is normally held in its uppermost position by the spring a²⁴. When the elevator N descends to its proper position, the lip a²⁵ is ordinarily carried out of registration with the slide a²⁶ and the casting mechanism is permitted to operate in the usual manner. In the present instance, the lip a²⁵ is pivotally mounted at J^a upon the rod a²³, and to its opposite end is connected the spring J¹, which tends to throw the lip upward to the position indicated in Fig. 4. It should be here noted that the slide a²⁶ is formed with a blunt or extended contacting surface, as distinguished from the sharp blade or edge shown in my application, Serial No. 533,124. Also pivotally mounted at J¹ upon the rod a²³ is the lever J, provided at its upper end with the projection or feeler J², and on its lower arm J³ with the pin or stud J⁵. Connected to the lever J and to the rod a²³ is the spring J⁴, which normally tends to hold the lever J in its retracted position, as shown in Figs. 1, 2 and 3. The spring J⁴ is stronger than the spring J¹, and the pin J⁵ on the arm J³ therefore acts on the pivoted lip a²⁵ to hold it in its normal or inoperative position, as also shown in the last mentioned figures.

The descent of the elevator N is governed and controlled by the keeper plate H connected to the mold wheel O. The keeper plate is provided at its upper outer corner with a projection or lug H³, and at its lower inner corner with a cut or recess H⁴. The lug H³ and the recess H⁴ vary in size and correspond to the particular dimensions and style of type employed, the lug H³ acting to check the descent of the elevator in proper relation to the mold, and the recess H⁴ serving to control the position of the movable lip a²⁵. It is to be noted that the position of the cut or recess must always have the same relation to the projection or feeler J², and therefore its depth must vary to correspond to the location of the other parts of the keeper plate. I preferably employ a separate plate H for each different size and style of type, each plate having the lug and recess suitably formed thereon, although it would still be within the scope of my invention to employ a single plate whereon the lug and recess could be adjustably proportioned. According to the size of the type, the special lug H³ serves to arrest the downward movement of the elevator N, see Fig. 134

3, so as to bring the lower ears of the matrices into correct relation to the grooves H^1 and H^2 , and thereby insuring the proper location of the selected characters upon the edge 5 of the slug. The cut or recess H^1 controls the position of the lever J , it being suitably located to pass over the projection or feeler J^2 and to permit its entrance therein, when the rod a^{23} is properly depressed.

16 The operation of the parts will now be clearly understood. When the elevator N descends to position so as to register the matrices Y carried thereby in relation to the grooves H^1 and H^2 , the rod a^{23} is acted upon 15 by the screw N^1 and is depressed to its lowermost position, as shown in Figs. 1 and 2. The mold wheel O then advances toward the elevator, and the cut or recess H^1 passes over the projection or feeler J^2 , and thus leaves 20 the lever J in its normal position with the pivoted lip a^{25} below and out of range with the slide a^{26} , which is simultaneously moved forward by the mold wheel O or the mold O^2 thereon. The rod a^{23} therefore fails to act 25 upon the tripping lever a^{22} and the casting proceeds in the usual manner. If, however, the elevator N fails to descend to the proper extent, that is to say, until it abuts against the lug H^3 , the rod a^{23} is not sufficiently depressed, leaving the projection or feeler J^2 30 in the path of the keeper plate H (see Fig. 4), whereupon the advance of the mold wheel O acts to turn the lever J about its pivot J^1 . This moves the other arm J^3 of 35 the lever in the opposite direction and removes the pin or stud J^5 from its normal engagement with the pivoted lip a^{25} , thus permitting the spring J^7 to throw the lip a^{25} upwardly into the path of the slide a^{26} . As 40 the slide is advanced by the contact therewith of the mold wheel O , and acting through the lip a^{25} , it moves the rod a^{23} to the dotted line position shown in Fig. 4, and simultaneously actuates the tripping lever 45 a^{22} to check the operation of the casting devices. In other words, the failure of the elevator to bring the line to the proper level in front of the mold stops the casting. It is to be noted that when the parts operate correctly, the lip a^{25} is located in its inoperative 50 position below the advancing slide a^{26} , but if the operation be incorrect, the lip a^{25} will be elevated into the path of the slide a^{26} so as to stop the machine, and without reference 55 to the extent of adjustment possible, for the reason that the blunt or extended operative face of the slide a^{26} permits it to act upon the lip through a considerable range, provided only that the lip is located somewhere 60 within its extreme limits. It will be seen that the provision of the parts previously described, and particularly the pivotal and yielding character of the lip a^{25} , thus gives the latter a greater extent of operation than 65 was permitted in the previous devices; and

that it will be brought into active relation to the slide a^{26} notwithstanding the considerably wider range of possible adjustment.

Having thus described my invention, its construction and mode of operation, what I claim and desire to secure by Letters Patent of the United States, is:

1. In a typographical machine, the casting devices comprising clutch controlling mechanism, the said mechanism including a 75 movable controlling member, a relatively movable element a^{25} mounted thereon, and means a^{26} cooperating therewith, together with additional means for moving the element a^{25} relatively to the controlling member and into operative relation to the means a^{26} .

2. In a typographical machine, the casting devices comprising clutch controlling mechanism, the said mechanism including a 85 controlling member, a relatively movable element a^{25} mounted thereon, actuating means therefor, and devices for shifting the said movable element relatively to the controlling member, whereby it is brought into 90 operative relation to the actuating means.

3. In a typographical machine, the combination of a mold, a vertically movable elevator for presenting matrices in casting relation thereto, clutch-controlling means operated by the elevator and operative to different extents, the said controlling means including an element a^{25} relatively movable with reference thereto, an actuating device therefor, and means to move said element 95 into operative relation to the actuating device in different positions of the clutch-controlling means.

4. In a typographical machine, the combination of the reciprocated mold, the elevator for presenting matrices thereto, the clutch controlling member a^{23} , the relatively movable lip a^{25} mounted thereon, the slide a^{26} to engage therewith, and supplemental means to vary the position of the movable 110 lip a^{25} .

5. In a typographical machine, the combination of the reciprocated mold, the elevator for presenting matrices thereto, the clutch controlling member a^{23} , the movable lip a^{25} mounted thereon, the slide a^{26} to engage therewith, with a device to govern the position of the movable lip a^{25} .

6. In a typographical machine, the combination of the reciprocated mold, the elevator for presenting matrices thereto, the clutch controlling member a^{23} , the movable lip a^{25} mounted thereon, the slide a^{26} to engage therewith, with the lever J to govern the position of the movable lip a^{25} and arranged 125 to be acted upon by the mold.

7. In a typographical machine, the combination of the reciprocated mold, the elevator for presenting matrices thereto, the clutch controlling member a^{23} , the movable lip a^{25} 130

mounted thereon, and the slide a^{26} to engage therewith, with the pivoted lever J arranged at one end to govern the position of the lip a^{25} and at its other end located to be acted upon by the mold.

8. In a typographical machine, the combination of the reciprocated mold formed with the recess II^1 , the elevator for presenting matrices to the mold, the clutch controlling member a^{23} , the movable lip a^{25} mounted thereon, and the slide a^{26} to engage therewith, with the pivoted lever J to govern the position of the lip, and located in proper relation to the recess II^1 of the mold so as to pass therein when the member a^{23} is properly actuated, or to be shifted by the mold to release the movable lip when the member a^{23} is insufficiently actuated.

9. In a typographical machine comprising casting mechanism, the said mechanism including a keeper-plate formed with grooves II^1 , II^2 , the stop lug II^3 at the upper edge thereof, and the recess II^4 in the lower edge thereof.

10. In a typographical machine comprising casting mechanism, the said mechanism including the keeper-plate formed with the stop lug II^3 at the upper edge thereof and with the recess II^4 in the lower edge thereof.

11. In a typographical machine, the casting devices comprising clutch controlling mechanism, the said mechanism including a controlling member movable to different operative positions and actuating means therefor, and a relatively immovable element mounted on one of said parts to establish an operative connection between them in the different operative positions of the controlling member.

12. In a typographical machine, the combination of a mold, a movable elevator for presenting matrices thereto, clutch-controlling mechanism adapted to be moved to inactive position by the presenting movement of said elevator, the said controlling mechanism comprising a relatively movable member, and means to move such member relatively to the controlling mechanism and into operative position without moving the said controlling mechanism as a whole.

In testimony whereof I hereunto set my hand this second day of August, 1911, in the presence of two attesting witnesses,

JOHN R. ROGERS.
